UNITED STATES PATENT OFFICE

2,165,890

PILE WIRE MOTION FOR LOOMS

James William Foster, Freehold, N. J.

Application January 22, 1938, Serial No. 186,421

1 Claim. (Cl. 139—42)

My invention relates to a wire motion mechanism for inserting and withdrawing the pile wires in the looms for the manufacturing of tapestry carpets or other pile fabrics, and has for an object to provide a mechanism that is simple and positive and arranged for great accuracy in adjustment.

A further object of the invention is to so construct the mechanism that the hopper or clamp will travel at two rates of speed, that is, the clamp will be withdrawn on the slower motion and inserted during the quicker motion.

Still another object of the invention is to provide a wire motion for pile wire looms that is relatively simple in construction and eliminating a number of parts heretofore necessary in the operation of the pile wire mechanisms.

Still another object of the invention is to provide a mechanism for inserting and withdrawing the pile wires that will be exceedingly sturdy in construction and so designed that it will withstand the hard usage to which a loom of this kind is subjected.

Still another object of the invention is to provide a wire motion for looms wherein the adjustments as to the length of the stroke and the timing may be regulated to a fine degree of accuracy, as not only is means provided for making what might be termed ordinary adjustments, but means is provided for making micrometric adjustments, so that a loom provided with a wire motion, about to be described, may be stepped up from thirty-eight picks a minute to between forty-two and fifty.

Still another object of the invention is to provide a wire motion that will cut down the usual breakage of the pile wires, as I have found in practice that where the ordinary loom will usually break from twelve to fourteen pile wires in a certain period of time, the present device will cut down such loss from three to four during the same period of time.

Still another object of the invention is to provide a wire motion that permits of a less number of parts than heretofore considered necessary; provides a smoother motion for the loom; entails less adjusting time; and, as heretofore mentioned, enables the loom to be run at twenty to thirty per cent higher rate of speed.

Still another object of the invention is to provide a wire motion that will be positive in action, easily adjusted, easily regulated, and with relatively few parts to get out of order. Also, the mechanism may be easily attached to looms

heretofore using other different forms of wire operating mechanism.

Still another object of the invention is to provide a wire motion wherein the length of the stroke for operating the hopper or clamp may be carefully adjusted and after which a further micrometric adjustment may be made between the driving pinion and a bevel gear, so that any fractional part of a tooth may be allowed for, or, in fact, the adjustment may be made to within a thousandth of an inch.

With these and other objects in view, the invention consists in certain new and novel features and combination of parts, as will be herein-after more fully explained and pointed out in the claim.

Referring now to the drawings showing a preferred embodiment and that much of a wire motion for a loom as necessary to illustrate the present invention,

Fig. 1 is an end elevation with the hopper or clamp about midway its travel and the actuating means in the correct relative position;

Fig. 2 is a fragmentary top plan view showing the wire-actuated mechanism and several of the wires that are to be operated;

Fig. 3 is an enlarged detail view showing the driving mechanism for the cable that actuates the wires, the mechanism being in the position at the starting of the loom;

Fig. 4 is a similar view but showing the parts at the end of the outward stroke and likewise the end of the outward movement of the cable;

Fig. 5 is a vertical sectional view showing the micrometric adjustable gear;

Fig. 6 is a bottom plan view thereof;

Fig. 7 is an enlarged sectional view taken on the line 7—7 of Fig. 2;

Fig. 8 is an enlarged sectional view taken on the line 8—8 of Fig. 1;

Fig. 9 is an enlarged fragmentary sectional view taken on the line 9—9 of Fig. 1.

Referring now to the drawings, it will be understood that I have shown only a detached part of the loom frame together with enough of the improved wire motion or mechanism sufficient to enable those skilled in the art to understand the construction and operation thereof.

Referring for the moment to Fig. 1, there is shown the frame 1 with the leg or pedestal 2 together with the other supports 3.

If the mechanism is to be attached to certain types of looms now in use, an additional frame member 4 will be inserted, to which will be secured the lower frame member 5. Pivoted, as at 6, in

the lower frame member 5 may be seen the lever 7 with its slot 8 formed therein, and to the left side of the lever (Fig. 1), it will be seen that there is the lug or ear 9, which is provided with a series of adjusting holes 10, to one of which will be pivotally secured an adjustable connecting link 11, shortly to be described.

Mounted just to the rear of the lever 7 is the relatively large crank disk 12, on which is adjustably mounted a stud 13, which is provided with the key portion or slide block 14 at its inner end to fit in the undercut guideway 15 formed in the crank disk 12, the stud being adjustable through the provision of the screw 16. Closely fitting about the stud 13 may be seen the bronze block 17, which will be held in position by the washers 18 and the nut 19. Thus, as the crank disk revolves and the lever 7 oscillates, the block may slide within the slot 8 of the lever, as will be readily appreciated. By providing a lever with a straight slot, the block 17 may be used to thus provide an accurate connection, there being no lost motion between the lever and the stud.

By adjusting the stud inwardly or outwardly of the disk, the throw of the lever may be regulated. Pivotally mounted in the same plane as the lever 7 may be seen the segment gear 20 with its teeth 21 designed to mesh with the driving pinion 22 mounted on the cross shaft 23, which shaft is suitably mounted in the bearings 24 and 25, the latter bearing being hung from the frame, as at 25.

The bearing 24 is bolted in position for quick removal, so that on the initial timing of the wire motion, the gear teeth of the pinion 22 may be dropped within the proper teeth of the segment gear 20, as shown in Fig. 3. Also located on this shaft 23 may be seen the cable drum 27. It is about this drum that the cable 28 is wound, the said cable passing about the opposite sheaves 29 and 30. The one bight 28^a of the cable is passed over the drum to the left (Fig. 1) and then secured to a spoke of the drum, whereas the other bight 28^b of the cable passes over the drum in the opposite direction and secured, so that when the drum is revolving, one bight pays off as the other bight takes up.

Pressing against the bights 29^a and 28^b may be seen the several idler rollers 31, which may be arranged to take up any slack as it appears in the cable 28.

Secured to the cable 28 is the clamp 32, often spoken of as a wire box or hopper, which is provided with the hook arm 33 that engages the various pile wires 34.

The wire guide and pile wires themselves form no part of the present invention, although it might be mentioned, as seen in Fig. 8, that the clamp or hopper is simplified over the usual construction. In Fig. 8 may be seen the yoke 35 of the hopper, which is clamped about the cable 28.

Referring now for the moment to Fig. 2, it will be seen that the crank disk 12 is mounted on the cross shaft 12^a, which shaft is suitably mounted in bearings and is provided about centrally of its length with an adjustable gear 36, which will be described in detail, that, in turn, meshes with the pinion 37 mounted on the shaft 38, while also mounted on this shaft 38 is the large gear 39, which, in turn, is operated by a pinion 40, which will be driven by a motor (not shown).

It will be remembered that the cable drum 27 is actuated by the oscillating segment gear 20, which, in turn, is connected with the oscillating lever, which latter is actuated by the relatively

large crank disk 12 mounted on the shaft 12^a. It will also be remembered that the length of the stroke may be varied by setting the stud 13 inwardly or outwardly of the crank disk; and that openings 10 are provided in the lever 7 for several adjustments of the link 11, which link is provided with a turnbuckle 11^a to provide for finer adjustments. Then, to provide a micrometric adjustment for the actuating mechanism, so that any part of a tooth may be allowed for, that is, between the gear 36 and pinion 37, I have provided a plate 36^a with its hub 36^b, which is splined, as at 36^c, to the timing shaft 12^a, on which, it will be remembered, is mounted the relatively large crank disk 12. The rear of the plate 36^a is provided with the radially extending arms 36^d. The gear 36 has the lugs 36^e arranged to, respectively, straddle the ends of the radial arms 36^d, as may be clearly seen in Fig. 6. These lugs are threaded to receive the adjusting screws 36^f.

Slots 36^e are formed in the gear through which the bolts 36^k pass into threaded openings in the plate 36^a for securely clamping the gear to the plate after adjustment is effected by the set-screws.

It will be noticed also that the plate 36^a has a hub which extends up within the gear for purposes of concentricity, as seen in Fig. 5. After the gear has been adjusted so that the exact desired meshing of the teeth between the gear and its pinion 37 is attained, that is, down to a micrometric measurement, the bolts 36^k passing through the slots 36^e in the gear 36 and into threaded openings in the plate 36^a will be locked up.

It will be appreciated that it is extremely important that the length of the stroke and the timing be just as accurate as it is possible to be made, due to the synchronizing of the different functions of a carpet weaving loom, and by providing the adjustments first-mentioned and then the micrometric adjustment of this gear on the driving shaft, which, in turn, it will be remembered, revolves the crank disk, operates the lever, and actuates the drum through the segment gear, the operation of the cable, together with its hopper or clamp for actuating the pile wires, can be controlled to the finest degree of accuracy.

In Fig. 3, I have shown the position of the segment gear 20, lever 7, and crank disk 12 for the starting of the loom, and when the parts are in this position, the hopper or clamp 32 on the cable would be to the extreme left of Fig. 1 and the cable and clamp about to start on the outward travel to pull the pile wire through the loops to sever the same.

It is desirable to have the pile wires move out of the shed more slowly than on their inward travel, because the loops are now bound about the pile wires and necessitate greater pressure than when the pile wire is being inserted.

By glancing at Fig. 3, the position of the crank disk 12 and the lever 7 is shown for the proper starting position, and the lever 7, on the rotation of the crank disk in a clockwise direction, will move over to the position shown in Fig. 4 and the stud 13 will have revolved from the point *a* around to the point marked *b*.

A completion of rotation of the crank disk will again cause the lever 7 to move over to the position shown in Fig. 3, while the stud is now traveling from the point *b* clockwise to the point *a*. Thus, the return stroke of the lever is much faster than its forward stroke, as is well known

and readily understood with a mechanism of this type.

Therefore, there is a relatively slow outward motion of the cable and its clamp to draw out the pile wire and a relatively quick motion for inserting another pile wire into the shed.

From Figs. 3 and 4, it will be seen that by the use of the turnbuckle 11^a in the link 11, an adjustment may be made between the segment gear 20 and the lever 1 and also the link 11 may be positioned in the desired opening 10 in the lug 9 on the lever, which openings 10, by the way, are located about centrally of the length of the lever, which is where they should be, so that the load to the connecting link is always about centrally of the lever.

As heretofore mentioned, the pinion 23 may be set in the proper tooth of the segment gear and the extra teeth to the right of the pinion, as shown in Fig. 3, are for the proper setting of the pinion with relation to the segment gear 20.

After the parts have all been adjusted for the proper synchronization of the functions outlined, no further adjustments will be necessary for a long continuous operation of the loom.

However, should it be necessary to change the length of the stroke or the timing of the several parts, it is but the matter of a few minutes, as the adjustable parts are all easily accessible.

From the foregoing, it will be seen that I have provided a wire motion for looms that is relatively simple in operation, dispensing with a number of parts heretofore found necessary, and, at the same time, by employing the various parts outlined, the timing and synchronization of the different parts may be adjusted with a fine degree of accuracy. As before stated, the speed of the loom may be stepped up to around fifty picks a minute.

I have also found in actual service that the various parts will withstand the hard usage to which they are put, thus overcoming any frequent shut-downs of the looms for repairs or adjustments.

Having thus described my invention, what I claim as new and desire to secure by Letters Patent is:

In a loom for weaving with pile wires, the combination of a wire box, a cable for imparting motion to the wire box, a cable drum and pulleys upon which the cable is mounted, a pinion associated with the cable drum, a segmental gear engaged by the pinion, an oscillating lever pivoted in substantially the same horizontal plane as the 15 pivotal point of the segmental gear, said lever having a slot therein, a relatively large crank disk having a radially adjustable stud for timing purposes, a block accurately fitting about said stud and slidably movable within the aforesaid 20 slot in the lever, said oscillating lever having a projecting ear substantially midway its length provided with openings for fastening purposes, an adjustable rod connected to said segmental gear and to an opening in said lever, said rod 25 communicating motion from the said crank disk to the said segmental gear to thereby operate said cable drum, a timing shaft for said crank disk, a main drive shaft for imparting motion to the said timing shaft and crank disk, and a 30 mitre gear connecting the two said shafts, said gear being adjustable in either direction to the width of one tooth to thereby micrometrically effect the final position of the cable drum through the said oscillating lever, adjustable rod, segmental gear, and pinion.

JAMES WILLIAM FOSTER.
